LEAF FLIPPER

Paul O. Unger, Elmhurst, Ill., assignor to Wilson-Jones Company, Chicago, Ill., a corporation of Massachusetts

Application May 19, 1939, Serial No. 274,533

1 Claim. (Cl. 129—4)

This invention relates to a leaf flipper particularly adapted for use in loose leaf binders to facilitate closing of the binder without tearing the sheets.

In loose leaf binders of the type wherein the sheet retaining means comprises a plurality of curved prongs which meet similar prongs to form rings the sheets impaled on the prongs must slide along the prongs when the binder covers are moved to closed position. It has been long known that in this closing operation the sheets quite often bind at the base of the ring and sometimes tear at the apertures. Many attempts have been made to minimize the friction between the sheets and the rings, but most of the structures have been relatively expensive and many have proved to be incapable of accomplishing the desired result.

It is an object of my invention to provide an inexpensive and efficient means for lifting the sheets of a ring binder relative to the rings when the binder is closed to prevent the sheets binding or dragging on the rings. Other objects of the invention will become apparent upon reading the following description taken in conjunction with the accompanying drawings, in which

Figure 1 is a fragmentary top elevation of a loose leaf binder illustrating one embodiment of the invention:

Figure 2 is an end elevation of the binder of Figure 1 with the covers open flat;

Figure 3 is a view similar to Figure 2 with the covers moved towards closed position:

Figure 4 is an enlarged fragmentary detail perspective view of the leaf flipper of Figures 1, 2 and 3;

Figure 5 is a perspective view of another embodiment of the invention;

Figure 6 is an end view of the embodiment of Figure 5;

Figure 7 is a perspective view of another embodiment of the invention;

Figure 8 is an end view of the embodiment of Figure 7;

Figure 9 is a view similar to Figure 1 showing another embodiment of the invention;

Figure 10 is an end elevation of the embodiment shown in Figure 9;

Figure 11 is an enlarged fragmentary detail perspective view of the leaf flipper of Figures 9 and 10; and

Figure 12 is a detail perspective view of the blank from which the sheet lifting members are formed.

In the drawings, the reference numeral 1 indicates a conventional loose leaf binder provided with a cover plate 2 and with divided ring sections 3 upon which leaf flippers may be impaled. One leaf flipper is positioned adjacent each cover and a plurality of sheets 4 is impaled on the rings 3 so as to lie between the leaf flippers. The leaf flippers must engage the inner edges of the sheets closest to the covers when the covers are moved from open to closed position and lift them slightly, relative to the rings, to prevent their binding so that the binder may be closed without tearing any of the sheets.

In Figures 1 to 4, a leaf flipper 5 comprises an apertured end sheet 6 having a plurality of sheet lifting members 7 rigidly secured thereto by rivets or eyelets 8. The member 7 comprises an attaching portion 9, a ledge 10 extending at approximately a right angle from the portion 9, and an abutment 11 which may be bent at approximately a right angle from the ledge 10. The ledge 10 is adapted to engage the inner edges of the outermost sheets. The abutment 11 is of a proper length to engage the cover plate 2 until the sheets 4 pass the critical point beyond which there is no danger of their binding when the binder is being closed. The critical point is approximately half the height of the ring sections. The lower surface 12 of the abutment 11 (Figures 2 and 3) is cam shaped to provide a rocking engagement with the cover plate 2 to minimize the friction between the parts when the binder is moved to closed position. The elongated cam shape of the lower surface 12 of the abutment 11 is of particular advantage in that it causes the fulcrum point around which the leaf flipper moves to change progressively as the binder is closed to maintain the apertures of the sheets in proper relation to the ring or prong sections.

In some loose leaf binders, particularly prong binders and visible ring binders, the prongs or ring sections are spaced very closely, (in some cases three-eighths of an inch) and the length of the ledge 10 must be limited to enable the sheet lifters to be used with binders of this type. Accordingly, it is preferred to bend the abutments 11 slightly more than ninety degrees relative to the ledge 10, as shown in Figure 1, to prevent the abutment 11 of one flipper from getting caught against the edge of the ledge 10 of the sheet lifter on the opposite flipper. This arrangement permits making the flippers alike so that no rights and lefts are required. Although it is preferred to form the sheet lifter 7 of sheet metal,

it is obvious that it might be molded of any suitable plastic composition.

The embodiment of Figures 5 and 6 shows a molded sheet lifter 13 riveted to an end sheet 14. The sheet lifter is provided with an abutment 15 spaced slightly off center relative to the ledge 16 to prevent the abutments from engaging each other. The lower surface 17 of the abutment is cam shaped just as in the previously described embodiment.

In Figures 7 and 8 the sheet lifters 18 may be formed of sheet metal, fiber or any suitable plastic composition. In the case of sheet metal the strips 19 could be riveted or eyeletted to the end sheet 20. If fiber or a plastic composition is used, the strips 19 can be cemented to the opposite surfaces of the end sheet. The doubled end of each strip 19 projects beyond the inner edge of the end sheet and is formed to provide a ledge 20 and an elongated cam shaped abutment 21.

The sheet lifters shown in Figures 9 to 12 are preferably formed of sheet metal. The blank shown in Figure 12 comprises a portion 22 adapted to be riveted to an end sheet 23. The ribbon like portion 24 is adapted to be bent to form an elongated cam shaped abutment 25 and the enlarged portion 26 is bent downwardly, as shown in Figure 11, to form the sheet engaging ledge. The projection 27 fits flush against the edge 28 of the portion 22 and is preferably welded thereto to provide a rigid structure. This embodiment is illustrated in connection with a binder of larger capacity than that shown in Figures 1, 2 and 3, but it will be understood that the operation of all embodiments of the leaf flipper is

the same and that any embodiment can be designed to function efficiently with any capacity binder. Since the elongated cam shaped abutment must remain in engagement with the cover plate until the lowermost sheet is lifted to approximately half the height of the ring it is obvious that each capacity of binder will require sheet lifters designed to fit that particular capacity to operate most efficiently.

10 Although I have described several embodiments of my invention in detail, it will be understood that the description thereof is illustrative, rather than restrictive, as many details may be modified or changed without departing from the spirit or scope of the invention. Accordingly, I do not desire to be restricted to the exact details of construction described, except as limited by the appended claim.

I claim:

In a loose leaf binder having a plurality of sheet retaining prongs and an arcuate cover plate, a leaf flipper comprising an end sheet fitting over the sheet retaining prongs and a plurality of sheet lifters secured to said end sheet, said sheet lifters each having a ledge adapted to engage the inner edges of a plurality of sheets mounted in said binder to lift said sheets relative to said sheet retaining prongs when the binder is closed and an elongated cam shaped surface to provide a rocking engagement with said cover plate, said cam shaped surface extending outwardly from said ledge and lying between the planes formed by the upper and lower edges of the ledge.

PAUL O. UNGER.
